ZIGZAG SEWING MACHINE ATTACHMENT
FOR STITCHING GLOVES AND THE LIKE

Philip Adragna, New York, N. Y.

Application September 18, 1940, Serial No. 357,224

3 Claims. (Cl. 112—98)

This invention relates to new and useful improvements in a zigzag sewing machine attachment for stitching gloves and the like.

More specifically the invention proposes a novel attachment which may be mounted on a twin needle zigzag sewing machine so that the machine is capable of sewing raised zigzag stitches. By raised zigzag stitches as used in this specification, it is meant that the fabric, leather or other sheet material which is sewed, has a raised zigzag portion, with the stitches across the base thereof to hold the raised portion in formation.

It is proposed that the attachment be associated with the usual rocker arm which is mounted on the side of the head portion of the zigzag sewing machine and which oscillates the needle bar. When the attachment is connected with this rocker arm it will operate in synchronization with the needle bar which is necessary for the proper operation of the device.

The invention proposes to arrange the attachment to include a linkage system which is arranged to be adjusted so that the zigzag sewing machine may be adjusted to sew zigzag raised portions of various sizes.

Still further the invention contemplates characterizing the attachment by a pair of downwardly extending fingers for extending along the sides of the twin needles of the zigzag sewing machine, to be cooperative with an upwardly extending finger mounted on a certain slide arranged beneath the plate which extends across the toothed fabric engaging foot of the sewing machine. It is proposed that these three fingers coact with each other to raise an area of the fabric, sheet leather or other material which is being sewed by the zigzag machine in a way so as to form the raised zigzag formation mentioned.

Still further the invention proposes the construction of an attachment as mentioned which is simple and durable and which may be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a zigzag sewing machine equipped with an attachment in accordance with this invention and having certain of the parts in an abnormal raised position for the sake of clarity.

Fig. 2 is a fragmentary elevational view of the base portion of Fig. 1 looking in the direction of the line 2—2 thereof; this view being described as fragmentary for the reason that many known portions of the standard zigzag machine have been omitted therefrom.

Fig. 3 is a fragmentary horizontal sectional view taken on the line 3—3 of Fig. 1.

Fig. 4 is a fragmentary vertical sectional view taken on the line 4—4 of Fig. 1.

Fig. 5 is a perspective view of the linkage system and associated parts comprising the attachment, illustrated *per se*.

Fig. 6 is a fragmentary horizontal sectional view taken on the line 6—6 of Fig. 5 but showing this section applied to the rocker arm of the zigzag sewing machine.

Fig. 7 is a fragmentary horizontal sectional view taken on the line 7—7 of Fig. 2.

Fig. 8 is a fragmentary elevational view of the bottom portion of the pressure foot and the needle bar of the machine, with portions of the attachment applied.

Fig. 9 is an elevational view of the parts shown in Fig. 8 looking from the right hand side and having certain of the parts in an abnormal raised position for the sake of clarity.

Fig. 10 is a fragmentary enlarged horizontal sectional view taken on the line 10—10 of Fig. 9.

Fig. 11 is a fragmentary perspective view of the pressure foot shown in Figs. 8 and 9.

Fig. 12 is a plan view of the plate which extends over the toothed fabric engaging foot of the sewing machine, and certain associated parts.

Fig. 13 is a fragmentary transverse sectional view taken on the line 13—13 of Fig. 12.

Fig. 14 is a fragmentary sectional view taken on the line 14—14 of Fig. 12.

Fig. 15 is a fragmentary elevational view of a piece of sheet material which has been stitched with the raised zigzag stitches in accordance with this invention.

Fig. 16 is a fragmentary vertical sectional view taken on the line 16—16 of Fig. 15.

The attachment for a zigzag sewing machine for stitching gloves and the like in accordance with this invention is used in combination with a standard zigzag sewing machine indicated generally by reference numeral 20. This machine has the usual head portion 20^a through which the conventional drive shaft passes, not illustrated on the drawings, for operating the needle bar 21 thereof. This needle bar is arranged in the usual way, that is, so that it may reciprocate upwards and downwards and at the same

time is capable of oscillating slightly laterally. This zigzag sewing machine is provided with the usual rocker arm 22 which is oscillated in the usual way by the drive shaft of the sewing machine, these details being omitted from this specification since they form no part thereof and these constructions are quite general.

A link 24 is connected between the needle bar 21 and the rocker arm 22. Such similar links have been previously used in zigzag machines. However, this link differs slightly from prior links in the fact that it is constructed of a pair of adjacent sections 24^a and 24^b which are adjustably connected together. Several screws 25 are mounted on one of these sections and pass through slots 26 formed in the other of the sections by which the link 24 may be adjusted to vary its length. The end of the link 24 which is connected with the rocker arm 22 is connected with this rocker arm in the customary fashion. More specifically, the link 24 is provided with a tubular bushing 27 passing through the end of the link. A stud 28 passes through the tubular bushing 27 and is formed with a dove-tail shaped head 29 slidably mounted in the usual groove 30 formed in the outer face of the rocker 22.

A nut 31 threadedly engages the stud 28 and is adapted to be turned tight so as to clamp the tubular bushing 27 fixedly in position along the length of the rocker arm 22. This tubular bushing 27 is of a slightly greater width than the width of the link 24, see Fig. 6, so that it is possible to fixedly clamp the bushing as stated while at the same time the link 24 is free to pivot. With this arrangement the nut 31 may be loosened and then the stud 28 may be shifted upwards or downwards upon the rocker arm 22 so as to vary the amplitude of oscillating of the link 24 and consequently of the needle bar 21.

A bracket 33 for supporting the two needles 34 of the twin needle zigzag sewing machine is mounted in the usual way upon the bottom of the needle bar 21. This bracket varies slightly from the conventional bracket in the fact that it is arranged to slidably support a pair of downwardly extending fingers 35. These downwardly extending fingers extend along the sides of the needles 34 and are vertically slidably mounted upon the bracket 33 in a certain way. The downwardly extending fingers 35 project from a cross head 35^a which is formed with splits 36. The rods 37 pass through the splits 36 and extend upwards and vertically slidably engage in the bracket 33. A clamp screw 38 is mounted through the split 36 of each downwardly extending finger 35 and works across the split 36 by which the downwardly extending fingers may be clamped upon the rods 37. A rectangular stem 43 projects from the cross head 35^a and slidably extends into a complementary opening formed in the bracket 33 to assist in retaining the cross head against turning. A screw 43^a in the bracket 33 extends into a slot 43^b in the stem 43 to permit the fingers 35 to remain in engagement with the goods being sewed after the needle bar 21 and needles 34 begin their upward movement. When the screw 43^a reaches the top of the slot 43^b, however, the crosshead 35^a and fingers 35 move upward with the needle bar and are lifted from the goods to permit movement of the goods before the next down stroke of the needles.

A coaxial spring 39 is mounted upon each rod 37 and operates between each downwardly extending finger and the bracket 33 in a manner so

that each finger is resiliently urged downwards. Thus each finger is capable of moving upwards and downwards relative to the bracket 33 under the resilient action of the spring 39. The sewing machine is provided with the usual pressure foot 43 which is cooperative with the usual toothed fabric engaging foot not illustrated on the drawings but which operates to advance the fabric or other goods being sewed. This pressure foot has an opening between the sides thereof through which the fingers 35, the needles 34 and a certain upwardly extending finger 45 pass. The cross-head 35^a is normally urged downward toward the top of the presser foot by the springs 39 and the fingers 35 extend through the presser foot to press and hold the goods when the needles are in engagement with the goods.

The zigzag sewing machine is provided with the usual plate 41 which is mounted across the base 20 of the machine and has openings 42 through which the toothed fabric engaging foot passes. So far the plate 41 is conventional; however, it now departs from the conventional design in the fact that it is formed with opening 44 located 25 between the openings 42. A certain upwardly extending finger 45 projects from this opening 44 as will be hereinafter more fully explained and the needles 34 are also constructed to pass through the opening 44.

30. A slide 46 is mounted transversely beneath the said plate 41. This slide passes through a pair of spaced bearing blocks 47 which are mounted upon the bottom of the base portion of the sewing machine. The upwardly extending finger 45 is 35 fixedly mounted on this slide 46. The opening 44 is wider than the width of the finger 45 so that the finger 45 may move laterally in the opening 44 when the slide 46 moves correspondingly. A linkage system is provided which connects the 40 slide 46 with the rocker arm 22 of the sewing machine.

The linkage system mentioned in the previous paragraph is for the purpose of oscillating the slide 46 in synchronization with the needle bar 21. This linkage system includes a bar 49 formed of two sections 49^a and 49^b which are adjustably connected with each other by screws 50 mounted on one of these sections and passing through slots 51 formed in the other of these sections. The bar 49 is pivotally connected with one end of the slide 46 by a pintle screw 52. That portion of the slide 46 between the bearing blocks 47 is reinforced or supported by a screw 53 which passes through a slot 54 formed in the slide. This screw 53 is threadedly engaged into the base of the sewing machine.

The bar 49 is pivotally connected with one end of a lever 55. This lever is pivotally mounted intermediate of its ends by a pintle 56. The other end of the lever 55 is connected with a link 57. This link is provided with a pin 58 which engages a slot 59 formed in the lever 55. The link 57 is pivotally connected by a pintle 60 with the bottom end of a pivotally mounted rod 61. The rod 61 extends upwards through an opening 62 formed in the base plate of the sewing machine. The rod 61 is pivotally supported intermediate of its ends by a pintle 63 which is mounted upon the side portion of the head of the sewing machine. The upper end of the rod 61 is pivotally connected by a pintle 64 with an adjustable link 65. The adjustable link 65 is formed from two sections, namely, section 65^a and section 65^b. One of these sections is provided with screws 66 which engage through slots

67 formed in the other of these sections. The adjustable link 65 has one of its ends pivotally mounted on the stud 23 which as previously explained is mounted upon the rocker arm 22.

The operation of the device is as follows:

The goods which is to be sewed with the raised zigzag portions is placed upon the base of the sewing machine directly beneath the twin needles 34. Then the pressure foot 40 which is grooved, in the usual manner of the foot of sewing machines for producing raised stitches, is lowered in the usual way so that the material is gripped. When this is done a small area of the material will be projected upwards because of the fact that the upwardly extending finger 45 projects above the top face of the plate 41, see Fig. 14. This finger 45 projects an area of the goods upwards between the fingers 35. Springs 39 resiliently urge the downwardly projecting fingers 35 down over the upwardly projected material so that the material is firmly held at the top as well as at the bottom. The machine is then operated in the usual way so that the needle bar 21 reciprocates up and down. Simultaneously the rocker arm 22 functions to oscillate the needle bar. Thus the machine operates.

The twin needles 34 are operated in opposite sides of the upwardly projected area of the goods, sewing the goods in the manner illustrated in Figs. 15 and 16. During the vertical reciprocation of the needle bar 21, the downwardly projecting fingers 35 will maintain their engagement with the upwardly projected material of the goods being sewn which is projected upwards by the finger 45. During this time the springs 39 are under tension.

As the needle bar 21 oscillates, the finger 45 will correspondingly oscillate so that the finger 45. During this time the springs 39 are under so in that the needle bar 21 is oscillated by the rocker arm 22, and it is the rocker arm 22 which oscillates the slide 46 through the linkage system previously described. Since the finger 45 is mounted on the slide 46 it oscillates in the same manner. The goods are sewn as illustrated in Fig. 15. In this figure the goods are generally indicated by reference numeral 70. The area 70^a thereof was projected upwards by the finger 45 and held in this position by the top downwardly projecting fingers 35. The needles 34 were sewing on the points 71 and 72 on the two sides of the upwardly projecting portion, and the shuttle of the machine is moving across the bottom of this portion producing the raised zigzag portions.

The amplitude of the zigzag formation may be varied merely by loosening the nut 31 and moving the stud 28 upwards and downwards along the rocker arm 22. When this adjustment is made, it may be necessary to properly adjust the linkage system so as to maintain the position of the upwardly projecting finger 45 in between the fingers 35. This may be done by loosening the screws 25, or the screws 61, or the screws 50, or any combination of these screws during the adjustment period. Once the adjustment has been made, these screws must be tightened.

A feature of the invention resides in the fact that since the amplitude of oscillation of the needle bar 21 and the finger 45 is controlled by the position of the stud 28 upon the rocker arm 22, the amplitude of oscillation of the needle bar 21 and the finger 45 will always be the same. This is necessary for the proper operation of the attachment.

It is to be understood that the finger 45 may

be of any desired shape and it may be placed either over the plate 41 or project from under the said plate through any suitable size and shape opening.

5 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

15 1. In a zigzag sewing machine having a pressure foot engageable against a piece of material being sewn and a reciprocating and oscillating needle bar carrying spaced needles and an oscillating finger extending upwards through an opening in said pressure foot to bulge said material upwards in the space between said needles and synchronized to follow the oscillating movement of said needles, a cross head slidably mounted on said needle bar and urged toward the top face of said pressure foot, downwardly extending fingers projecting from said cross head and projecting through the opening in said pressure foot to engage the material on either side of said oscillating finger to hold the material against the sides of said oscillating finger, and means for continually urging said cross head toward said pressure foot regardless of the reciprocative motion of said needle bar.

20 2. In a zigzag sewing machine having a pressure foot engageable against a piece of material being sewn and a reciprocating and oscillating needle bar carrying spaced needles and an oscillating finger extending upwards through an opening in said pressure foot to bulge said material upwards in the space between said needles and synchronized to follow the oscillating movement of said needles, a cross head slidably mounted on said needle bar and urged toward the top

25 face of said pressure foot, downwardly extending fingers projecting from said cross head and projecting through the opening in said pressure foot to engage the material on either side of said oscillating finger to hold the material against the sides of said oscillating finger, and means for continually urging said cross head toward said pressure foot regardless of the reciprocative motion of said needle bar.

30 3. In a zigzag sewing machine having a pressure foot engageable against a piece of material being sewn and a reciprocating and oscillating needle bar carrying spaced needles and an oscillating finger extending upwards through an opening in said pressure foot to bulge said material upwards in the space between said needles and synchronized to follow the oscillating movement of said needles, a cross head slidably mounted on said needle bar and urged toward the top

35 face of said pressure foot, downwardly extending fingers projecting from said cross head and projecting through the opening in said pressure foot to engage the material on either side of said oscillating finger to hold the material against the sides of said oscillating finger, and means for continually urging said cross head toward said pressure foot regardless of the reciprocative motion of said needle bar.

40 4. In a zigzag sewing machine having a pressure foot engageable against a piece of material being sewn and a reciprocating and oscillating needle bar carrying spaced needles and an oscillating finger extending upwards through an opening in said pressure foot to bulge said material upwards in the space between said needles and synchronized to follow the oscillating movement of said needles, a cross head slidably mounted on said needle bar and urged toward the top

45 face of said pressure foot, downwardly extending fingers projecting from said cross head and projecting through the opening in said pressure foot to engage the material on either side of said oscillating finger to hold the material against the sides of said oscillating finger, and means for continually urging said cross head toward said pressure foot regardless of the reciprocative motion of said needle bar.

50 5. In a zigzag sewing machine having a pressure foot engageable against a piece of material being sewn and a reciprocating and oscillating needle bar carrying spaced needles and an oscillating finger extending upwards through an opening in said pressure foot to bulge said material upwards in the space between said needles and synchronized to follow the oscillating movement of said needles, a cross head slidably mounted on said needle bar and urged toward the top

55 face of said pressure foot, downwardly extending fingers projecting from said cross head and projecting through the opening in said pressure foot to engage the material on either side of said oscillating finger to hold the material against the sides of said oscillating finger, and means for continually urging said cross head toward said pressure foot regardless of the reciprocative motion of said needle bar.

60 6. In a zigzag sewing machine having a pressure foot engageable against a piece of material being sewn and a reciprocating and oscillating needle bar carrying spaced needles and an oscillating finger extending upwards through an opening in said pressure foot to bulge said material upwards in the space between said needles and synchronized to follow the oscillating movement of said needles, a cross head slidably mounted on said needle bar and urged toward the top

65 face of said pressure foot, downwardly extending fingers projecting from said cross head and projecting through the opening in said pressure foot to engage the material on either side of said oscillating finger to hold the material against the sides of said oscillating finger, and means for continually urging said cross head toward said pressure foot regardless of the reciprocative motion of said needle bar.

70 7. In a zigzag sewing machine having a pressure foot engageable against a piece of material being sewn and a reciprocating and oscillating needle bar carrying spaced needles and an oscillating finger extending upwards through an opening in said pressure foot to bulge said material upwards in the space between said needles and synchronized to follow the oscillating movement of said needles, a cross head slidably mounted on said needle bar and urged toward the top

75 face of said pressure foot, downwardly extending fingers projecting from said cross head and projecting through the opening in said pressure foot to engage the material on either side of said oscillating finger to hold the material against the sides of said oscillating finger, and means for continually urging said cross head toward said pressure foot regardless of the reciprocative motion of said needle bar.

80 8. In a zigzag sewing machine having a pressure foot engageable against a piece of material being sewn and a reciprocating and oscillating needle bar carrying spaced needles and an oscillating finger extending upwards through an opening in said pressure foot to bulge said material upwards in the space between said needles and synchronized to follow the oscillating movement of said needles, a cross head slidably mounted on said needle bar and urged toward the top

continually urging said cross head toward said pressure foot regardless of the reciprocative motion of said needle bar, said slidable mounting of said cross head comprising a bracket mounted on said needle bar, and spaced rods having their bottom ends fixedly attached to said cross head and their top ends slidably extended into complementary openings formed in said bracket, said

means, comprising resilient members on said rods urging said cross head downwards, said resilient members comprising expansion springs coaxially mounted on said rods and operating between the adjacent faces of said bracket and said cross head.

PHILIP ADRAGNA.
